UNITED STATES PATENT OFFICE.

BERGER STOCKFLETH, OF BERRIEN SPRINGS, AND FREDERICK W. BURGER, OF NILES, MICHIGAN, ASSIGNEES TO CLARK TRACTOR COMPANY, OF BUCHANAN, MICHIGAN, A CORPORATION OF MICHIGAN.

TIERING MACHINE.

Application filed February 9, 1925. Serial No. 7,947.

Our invention relates to portable elevating apparatus or tiering machines of the general type shown and described in our pending application, Serial No. 711,822, filed 5 May 8, 1924, in which the elevating apparatus is carried on a supplemental frame detachably connected with the frame of a motor vehicle such as a shop tractor, said supplemental frame being supported on 10 wheels so that the load is sustained by such wheels, and being capable of moving vertically independently of the tractor frame. The elevating or hoisting devices are actuated by power derived from the motor 15 that propels the tractor. The object of our present invention is to provide an improved tiering machine in which the above-mentioned characteristic features of the machine of our said application are retained, but in 20 improved form, and also to provide certain other improvements by which the elevating apparatus will be made to operate with a greater degree of efficiency and by which also the machine as a whole will be better 25 adapted to meet the requirements of the uses to which it may be put. We accomplish our object as illustrated in the accompanying drawings and as hereinafter described. What we regard as new is set forth in the 30 claims.

In the accompanying drawings,—

Fig. 1 is a side elevation of our improved elevating apparatus applied to a shop tractor, the rear portion of the tractor being 35 omitted;

Fig. 2 is a view partly in plan and partly in section on line 2—2 of Fig. 1;

Fig. 3 is a view partly in plan and partly in section on line 3—3 of Fig. 1;

Fig. 4 is a partial vertical section on line 4—4 of Fig. 2, some parts being broken away;

Fig. 5 is a horizontal section on line 5—5 of Fig. 4, looking up;

Fig. 6 is an end view, some parts being in section; and

Fig. 7 is a diagrammatic view illustrating the course of the hoisting chains.

In the embodiment of our invention illustrated in the accompanying drawings our improved elevating apparatus is designed to be applied to and operated by a motor vehicle in the form of a small shop tractor 8 comprising

a frame 9 mounted on dirigible and propelling wheels substantially as shown and described in our said pending application. The propelling wheels are not illustrated, but it will be understood that they are preferably of the usual type employed in connection with motor vehicles, arranged to be driven by a propeller shaft through suitable differential gearing. Mounted on the frame 9 is the usual motor A, preferably of the internal combustion type, which, through suitable intermediate gearing, is arranged to drive the propelling wheels in either direction. Said motor is also arranged to drive a power take-off shaft 10 telescopically connected with suitable power transmission devices contained in a housing 11 shown in Fig. 1. The arrangements for this purpose are preferably those shown and described in our application of even date herewith for improvements in shop tractors, and for the purposes of our present application it will suffice to say that the shaft 10 is telescopically connected with said transmission devices, and may be disconnected therefrom by drawing it forward out of the housing 11. The transmission mechanism 15 is contained in a casing or hood 12 on which is placed the operator's seat 13. A lever 14 is provided for controlling the operation of the take-off shaft 10 by the motor A, as described in our said shop tractor application.

The front of the tractor is supported on one or more dirigible wheels 15 mounted centrally under the tractor frame and arranged to be steered by a steering wheel 16 carried by a steering column 17 that is connected with the dirigible wheel in any suitable way. At the front of the tractor frame an upright curved plate 18 is provided that serves not only as a dashboard but also as a head or abutment by which the tractor may be employed to push loads when the elevating apparatus is disconnected therefrom.

Our improved elevating apparatus, with which our present application is more immediately concerned, comprises a substantially U-shaped yoke or supplemental frame 19 having side arms 20, 21 that extend alongside the tractor frame 9 at opposite sides 105 thereof, as best shown in Fig. 2, and are

detachably connected therewith by springs 22, 23 and bolts 24, 25, respectively. By withdrawing the bolts 24, 25 the supplemental frame 19 may be disconnected from the tractor frame leaving the tractor in condition for other uses. The supplemental frame 19 is supported on its own wheels 26, 27, which are mounted in the manner of caster wheels at opposite sides of the front portion of the supplemental frame and preferably slightly in advance of the dirigible wheel 15. As shown in Figs. 1 and 6, said wheels 26, 27 are mounted in yokes 28 having upright spindles that are journaled in suitable bearings mounted in sleeves 29, 30, preferably integral with the supplemental frame 19, as illustrated in Fig. 6. The wheels 26, 27, therefore, are adapted to turn about vertical axes to conform to changes in direction of the travel of the tractor. Also, the supplemental frame 19 is free to move up and down independently of the tractor frame, subject to the restraint afforded by the springs 22, 23. The hoisting mechanism, all of which is mounted on this supplemental frame so that its weight is carried on the wheels 26, 27, will now be described.

Secured to the central curved portion of the supplemental frame 19 is an upright curved plate 31 that is made sufficiently heavy to withstand the strains to which it is subjected, and is firmly secured in place, preferably by providing the frame 19 with flanges 32, 33, 34 at its upper and lower margins, the plate 31 being riveted to said flanges, as shown in Figs. 2 and 6. To the central part of the plate 31 is firmly secured an I-beam 35, the lower end of which terminates a short distance above the supplemental frame 19, as shown at 36 in Fig. 4, while its upper end extends to the top of an elevator frame hereinafter described. Extending downward from the lower end of the I-beam 35 is another I-beam 37 that forms a downward continuation of the I-beam 35, but as shown in Fig. 4 said I-beam 37 is cut away at the rear to accommodate the central portion of the frame 19, and its front surface is inclined rearwardly toward its lower end, as indicated at 38 in Fig. 4. The I-beam extension 37 terminates a short distance above the ground. The beam 37 is firmly secured to the lower portion of the plate 31 by rivets 39 that pass through ears 40 at the opposite sides of said beam, as shown in Fig. 6.

Also supported by the plate 31 is an elevator frame comprising two oppositely-disposed channel beams 41, 42, said beams being disposed vertically with their channels on the inside, as best shown in Fig. 2, and they are firmly supported by bracing plates 43, 44 by which they are attached to the plate 31, as shown in said figure. The lower ends of the beams 41, 42 are also secured directly to the supplemental frame 19 by be-

ing riveted to flanges 45, 46 that project forward from said frame at opposite sides thereof, as shown in Fig. 6.

The upper end portions of the channel beams 41, 42 are cross-connected at the front and rear respectively by angle bars 47, 48 and gusset plates 49, 50 that brace the parts together, as shown in Fig. 5, from which it will be seen that the upper end of the I-beam 35 is also secured to the cross-bar 48. The bars 47, 48 are also connected together near their ends by flat bars 51, 52 that extend over the upper ends of the channel beams 41, 42, as best shown in Fig. 5. By this construction we provide a very strong and rigid elevator frame for supporting the operating parts of the hoisting apparatus.

Mounted at the upper end of the elevator frame is a transverse shaft 53 that extends through vertical slots 54 in the channel beams 41, 42, as shown in Fig. 5, and is supported by hangers or U-bolts 55, 56 secured to the bars 51, 52, respectively, so that they depend therefrom in the channels of the channel beams 41, 42, as best shown in Figs. 5 and 6. The arrangement is such that the shaft 53 is supported a short distance below the bars 51, 52 so that by adjusting the hangers 55, 56 vertically either end of the shaft 53 may be vertically adjusted independently of the other. The vertical adjustment of said hangers may be made by means of nuts 57 screwed on the upper ends thereof above the plates 51, 52, as shown in Figs. 4 and 6. The purpose of providing for this adjustment of the shaft 53 will be hereinafter explained.

As best shown in Figs. 5 and 6, the end portions of the shaft 53 extend some distance beyond the channel beams 51, 52, and upon the projecting end portions of said shaft are loosely mounted sheaves 58, 59, each of which is double, that is to say, each sheave is provided with two channels 60, 61 to receive the hoisting chains. The channels of said sheaves are suitably shaped to receive and engage the links of the hoisting chains so as to prevent slippage thereof, as best shown at the left in Fig. 6. The end portions of the shaft 53 are provided with oil ducts 62 that communicate through passages 63 with the peripheral portions of said shaft upon which the sheaves 58, 59 bear, so that said bearing surfaces may be properly lubricated, and to that end the ends of the shaft are equipped with oil cups 64 for supplying lubricant to the ducts 62. Preferably shields or housings 65 are mounted on the end portions of the shaft 53 over the sheaves 58, 59, as shown in Figs. 5 and 6.

From the foregoing description it will be seen that the channel beams 41, 42 constitute guide rails at opposite sides of the elevator frame disposed below the shaft 53 and the sheaves mounted thereon, and that the I-

beam 35 constitutes a central or intermediate guide rail that is supported in fixed relation to the other two guide rails. These guide rails are designed to guide a traveling carriage arranged to move vertically on the elevator frame, and to tilt about a transverse axis, as will now be described.

As best shown in Figs. 2, 3 and 4, the carriage comprises a frame 66 somewhat longer than the distance between the guide rails 41, 42 and provided at its upper margin with upwardly and rearwardly projecting arms 67, 68 in which is journaled a shaft 69 having mounted on its ends rollers 70, 71, as best shown in Figs. 3 and 6. These rollers are adapted to run in the channels of the guide rails 41, 42 and they are provided with flanges 72, 73 which serve to keep the shaft 69 and consequently the frame 66 in the proper position. The frame 66 also carries an intermediate roller 74 having flanges 75, 76 at its opposite margins, as shown in Fig. 3, which roller is mounted upon a shaft 77 supported by the frame 66 in such position that said roller is adapted to run on the front face of the intermediate guide rail 35, as shown in Figs. 2 and 4. As clearly shown in Fig. 4, the roller 74 is located a considerable distance below the rollers 70, 71, and its axis normally lies slightly forward of the transverse vertical plane of the axis of the shaft 69 that carries the rollers 70, 71. Thus the carriage is normally held against tilting about a transverse axis. This condition obtains at all times except when the carriage descends far enough so that the roller 74 rides upon the inclined portion 38 of the intermediate guide rail 35, as indicated by dotted lines in Fig. 4. In the latter circumstance the weight of the carriage and its load, if any, will cause said carriage to tilt about a transverse axis, since the inclination of the inclined portion 38 will permit the roller 74 to move rearwardly with reference to the rollers 70, 71. The carriage carries a load carrying member preferably comprising a platform or table 78, supported on forwardly-extending arms 79 having upright members 80 that are firmly secured in recesses 81 provided at the front of the frame 66 of the carriage, and secured by bolts 82, as shown in Fig. 3. The arms 79 are so shaped that when the carriage is in its normal position, that is to say, any position above the inclined portion 38 of the guide rail 35, the platform 78 will incline downward slightly toward the rear, to guard against its allowing the load to slip off, and the purpose of providing the inclined portion 38 is to permit the carriage 66 to tilt when it is in its loading position so that the platform 78 will then assume a horizontal position, as indicated by dotted lines in Fig. 4, thereby making it easier to deposit the load thereon, since then a vehicle such as a

lift truck may be wheeled over the platform and its load deposited directly thereon without its being necessary to perform that work manually. When the carriage is hoisted high enough so that the roller 74 passes above the inclined portion 38 of the guide rail 35 the platform again assumes its inclined position, as shown in full lines in Fig. 4.

The carriage is raised or lowered by means of hoisting chains, or equivalent devices, 83, 84, best shown in Figs. 6 and 7. The chains 83 are connected at one end with the end portions of the carriage, as by swivels 85, 86, and run over the outer grooves of the sheaves 58, 59 respectively, their opposite ends being preferably connected with the elevator frame, as indicated at 90 in Fig. 7. The slack incident to the vertical movement of the carriage may be permitted to hang loosely, as indicated in Fig. 7. By rotation of the sheaves 58, 59, therefore, the carriage may be raised or lowered, as desired. Power is applied to said sheaves to rotate the same by means of the hoisting chains 84, which are of the endless type, the upper bights of said chains running over the inner grooves of the sheaves 58, 59, while the lower bights thereof are looped around driving sheaves 87, 88 carried by the hoisting shaft 89, shown in Figs. 2 and 6. Fig. 7 clearly illustrates the course of the chains 83, 84 at one side of the machine, and it will be understood that the chains at the other side thereof are similarly arranged. The purpose of providing for separate vertical adjustment of the end portions of the shaft 53, on which, as previously explained, the sheaves 58, 59 are loosely mounted, is to take up any looseness due to stretching of the chains 84, so that said chains may be maintained taut around the driving sheaves 87, 88, and the sheaves 58, 59. Obviously by screwing the nuts 57 down on their respective U-bolts said bolts may be drawn up toward the bars 51, 52 by which they are supported, thereby raising the shaft 53. Either of said bolts may be adjusted independently of the other so that the proper tension may be maintained on the two chains 84, notwithstanding the fact that they may stretch unequally.

The hoisting shaft 89 is mounted at one end in a suitable bearing 91 carried by a standard 92 that rises from the frame 19 at one side thereof, as shown in Fig. 6, and the opposite end of said shaft is non-rotatably connected with a worm wheel 93 mounted in a housing 94 at the opposite side of said frame. Said worm wheel meshes with a worm 95 mounted in an extension 96 of the housing 94 and suitably supported on the frame 19, as also shown in Fig. 6. The worm 95 is connected with a shaft 97 that extends rearwardly through the housing 96, as shown in Fig. 2, and is connected by a flexible coupling 98 with a shaft 99 that

is in turn connected by a flexible coupling 100 with the power take-off shaft 10. By this construction, therefore, the shaft 89 may be rotated in either direction by power derived from the motor, thereby driving the hoisting chains in either direction and accordingly raising or lowering the load sustaining carriage. The connections for driving the hoisting shaft 89 from the tractor motor are not herein claimed, as devices of the same character form a part of the subject-matter of our separate application of even date herewith for improvements in portable cranes.

15 So far as we are aware we are the first in the art to provide an elevating apparatus or tiering machine of the type described, in which provision is made for adjusting the chains at opposite sides of the elevator frame, either simultaneously or separately, so as to maintain the bight of said chains taut around the driving sheaves, and we also believe ourselves to be the first to provide for guiding and tilting the load-carrying platform, or equivalent support, in the manner described, so that it will assume a favorable position for loading and an inclined position for hoisting purposes, and the construction by which these features are embodied in practical form constitutes the subject-matter of our present application.

20 While we prefer to use hoisting chains, it will be understood that any other suitable flexible hoisting means of such character that slippage will be prevented may be employed. The term "hoisting chain", therefore, as herein used is to be construed accordingly.

25 What we claim as our invention and desire to secure by Letters Patent, is—

30 1. A tiering machine comprising an elevator frame, having oppositely disposed channeled guides, a carriage movable vertically on said frame between said guides and having a load-carrying member, means running in said guides and pivotally connecting the carriage therewith to tilt about a transverse axis, flexible hoisting means for said carriage, and means between said guides 35 for normally holding said load carrying member against tilting, and for allowing it to tilt when it approaches its lowermost position.

35 2. A tiering machine comprising an elevator frame, a carriage movable vertically on said frame and having a load-carrying member, means pivotally connecting the end portions of said carriage with the frame to tilt about a transverse axis, flexible hoisting means for said carriage, and guiding means located between the ends of the carriage and cooperating with said carriage as the same is moved vertically to tilt said load-carrying member.

40 3. In a tiering machine, the combination

45 with an elevator frame comprising laterally-disposed vertical guides and an intermediate vertical guide, said intermediate guide being inclined rearwardly adjacent to its lower end, of a carriage movable vertically on said elevator frame and having rollers operating on said laterally-disposed guides, and a roller located between and below said rollers and running on said intermediate guide, a forwardly-extending load-supporting member carried by said carriage, and flexible hoisting devices for said carriage.

50 4. In a tiering machine, the combination with an elevator frame comprising oppositely-disposed channeled guides and a guide rail between said guides, the lower end portion of said guide rail being inclined rearwardly, of a carriage having rollers operating in the channels of said guides and a member located between and below said rollers and bearing on said guide rail, a forwardly-extending load-supporting member carried by said carriage, and flexible hoisting devices for said carriage.

55 5. A tiering machine comprising an elevator frame, a carriage movable vertically on said elevator frame, driving sheaves mounted on the lower portion of said elevator frame at opposite sides thereof, means for driving said sheaves, sheaves mounted at the upper portion of the elevator frame over said driving sheaves, hoisting chains at opposite sides of the elevator frame, each of said chains extending over one of the upper sheaves and having a bight extending around and operatively engaging one of the driving sheaves, means actuated by said hoisting chains for moving the carriage vertically, and means for vertically adjusting said upper sheaves.

60 6. A tiering machine comprising an elevator frame, a carriage movable vertically on said elevator frame, driving sheaves mounted on the lower portion of said elevator frame at opposite sides thereof, means for driving said sheaves, sheaves mounted at the upper portion of the elevator frame over said driving sheaves, hoisting chains at opposite sides of the elevator frame, each of said chains extending over one of the upper sheaves and having a bight extending around and operatively engaging one of the driving sheaves, means actuated by said hoisting chains for moving the carriage vertically, and means for vertically adjusting said upper sheaves independently of each other.

65 7. A tiering machine comprising an elevator frame, a carriage movable vertically on said elevator frame, driving sheaves mounted on the lower portion of said elevator frame at opposite sides thereof, means for driving said sheaves, a shaft mounted at the upper portion of the elevator frame, sheaves loosely mounted on the end portions
